UNITED STATES PATENT OFFICE.

HARRY WATKINS, OF SYRACUSE, NEW YORK, ASSIGNOR OF ONE-HALF TO
D. H. GOWING, OF SAME PLACE.

MANURE-SPREADER.

SPECIFICATION forming part of Letters Patent No. 362,048, dated April 26, 1887.

Application filed July 14, 1886. Serial No. 207,967. (No model.)

To all whom it may concern:

Be it known that I, HARRY WATKINS, of Syracuse, in the county of Onondaga, in the State of New York, have invented new and useful Improvements in Manure-Spreaders, of which the following, taken in connection with the accompanying drawings, is a full, clear, and exact description.

This invention relates to that class of manure-spreaders in which a cart or wagon is provided with a traveling floor at the bottom of its body, which floor gradually conveys the manure from the forward end of the body toward the rear end thereof, at which latter end the manure is cast and distributed from the vehicle by means of a rotary beater armed with radial spikes; and the invention consists in an improved construction and combination of some of the most essential parts of the machine, whereby the same is rendered more effective in its operation, all as hereinafter more fully described, and specifically set forth in the claims.

In the annexed drawings, Figure 1 is a side elevation of my improved manure-spreading machine. Fig. 2 is a plan view of the same, with a portion of the traveling floor broken away to illustrate the subjacent rollers which support the central portion of said floor. Fig. 3 is an enlarged view of that portion of the axle or driving shaft to which are attached the devices for transmitting motion from the traction-wheels to the traveling floor and beater. Fig. 4 is a transverse section on line *x x*, Fig. 3. Fig. 5 is a transverse section on line *y y*, Fig. 3. Fig. 6 is a longitudinal section of the traveling floor. Fig. 7 shows detached plan views of the endless chains which constitute a part of the traveling floor. Fig. 8 is an enlarged transverse section of the ratchet-wheel and pawl-carrying arms, by which motion is transmitted to the shaft which carries one of the sets of wheels on which the traveling floor is mounted. Fig. 9 is an enlarged detached view of the worm or screw which imparts the requisite lateral movement to the shifting-lever of the clutch. Fig. 10 is an enlarged detached side view of the standard on which the beater and its driving-gear and sprocket-wheel are pivoted; and Fig. 11 is an enlarged transverse section on line *z z*, Fig. 1.

Similar letters of reference indicate corresponding parts.

A represents the axle, which constitutes the main driving-shaft of the machine. On said axle is mounted, in any suitable and well-known manner, the body or box O.

W denotes the carrying or traction wheels, which are mounted loosely on the axle A. To the inner side of the hub of each traction-wheel is connected a pawl, T, and adjacent to said hub is a ratchet-wheel, P, which is rigidly secured on the axle, the pawl being arranged to engage the ratchet-wheel P when the traction-wheels are in their forward movement. The two pawl and ratchet connections allow each wheel to impart motion to the axle independent of the other wheel, and in turning the machine around the two wheels are allowed to turn in opposite directions or at different speeds.

The inner face of one of the ratchet-wheels P is formed with a clutch-face, *n'*, and adjacent to said clutch-face *n'* is a corresponding face, *n*, which is rigidly secured to the side of a sprocket-wheel, C, and the latter is loosely mounted on the axle A. Over and between the two clutch-faces *n* and *n'* slides a clutch, *o*, which has sufficient lateral play to allow it to be shifted toward the sprocket-wheel C to clear the clutch-face *n'*, as illustrated in Fig. 3 of the drawings, and by sliding the clutch *o* toward the ratchet-wheel P the said clutch becomes engaged with the clutch-face *n'* without losing its hold on the clutch-face *n*, and thus motion is transmitted to the sprocket-wheel C from the traction-wheel W when the latter is in its forward movement. To the inner side of the sprocket-wheel C is rigidly attached an eccentric, *e*, for the purpose hereinafter explained.

It will be observed that by the aforesaid construction and combination of parts I am enabled to transmit motion to both the sprocket-wheel C and eccentric *e* by one and the same clutch.

It is obvious that a crank may be used in lieu of the eccentric; hence I do not limit myself in this respect.

Across the bottom of the front end of the body O is extended a shaft, U, journaled in suitable bearings on said body. To one end

of this shaft is rigidly attached a ratchet-wheel, R. At the side of this ratchet-wheel are two arms, a a, pivoted independently of each other on the shaft U, and extending in opposite directions therefrom. On the free ends of these arms are pivoted pawls b b, engaging the ratchet-wheel at diametrically-opposite points.

At a suitable distance between the ratchet-wheel R and axle A is a rock-arm, D, pivoted 10 on the side of the body O, and to the lower end of this rock-arm are connected two rods, c c, which are extended to and connected with the free ends of the arms a a. The upper end of the rock-arm is slotted longitudinally, and 15 through the slot thereof is extended a coupling pin or bolt, to which is connected the forward end of the eccentric-rod d, the rear end of which is connected with the eccentric e, hereinbefore referred to. By means of this 20 eccentric and eccentric-rod the rock-arm D receives an oscillatory motion, and thus motion is transmitted to the arms a a by means of the rods c c. Said rods being connected to the rock-arm at one and the same end, 25 causes the two arms a a to move simultaneously in the same direction, and as the pawl b of one arm a engages the ratchet-wheel R and turns the same the pawl of the other arm a slides freely upon the ratchet-wheel, and the 30 alternate engagements of said pawls with the ratchet-wheels during the oscillations of the rock-arm D produces a nearly-continuous rotation of said ratchet-wheel and its shaft U.

By shifting the connection of the eccentric- 35 rod d on the slotted rock-arm D, so as to bring it a greater or less distance from the fulcrum thereof, the rotation of the ratchet-wheel and its shaft can be regulated to the desired speed.

On the shaft U, in the center of the front 40 end of the body O, is a chain-wheel, V, which is rigidly attached to said shaft, so as to rotate therewith, and a similar chain-wheel, V', is arranged in the center of the rear end of the machine. On the said chain-wheels runs 45 an endless chain, r, which is propelled with the upper half toward the rear end of the body O by the forward wheel, V, when rotated as aforesaid. Across the top of the links, about one-half of the length of the chain r, are 50 firmly secured wooden slats t t, which form the manure-carrying floor. These slats are of rectangular form in cross-section, and in order to render the floor smooth and at the same time tight, so as to prevent the manure from 55 entering between the slats, I secure to one of the edges of each slat a plate, s, which projects therefrom and laps onto the adjacent slat t, which is provided along one edge of its top with a recess, in which the overlapping portion of the plate is countersunk, as illustrated in Fig. 6 of the drawings. Said plates also 60 protect the slats from injury from the spikes of the beaters. The ends of the slats are connected together by similar chains, r' r', and 65 ride upon longitudinal ledges u on the side sills of the body O, by which ledges the ends

of the slats are supported, as best seen in Fig. 3 of the drawings.

There are a sufficient number of slats secured to the chains to form a floor reaching 70 from end to end of the body O above the wheels V V', and to the rearmost slat is secured a breast, E, which serves to prevent the manure from falling from the forward end of the floor.

B represents the so-called "beater," pivoted on standards F, secured to the rear end 75 of the body O. Said beater is armed with radial spikes w, by means of which it casts and distributes the manure from the rear end of 80 the body O. The beater receives a rotary motion by means of a pinion, h, secured to one end thereof, and meshing in a gear, k, which is pivoted on the standard F, and has secured to its side a small sprocket-wheel, l, which is 85 connected with the large sprocket-wheel C by a drive-chain, m.

In order to permit of compensating for the wear of the drive-chain and taking up the slack of said chain, I provide the standard F 90 with a segmental slot, g, described from the center of the journal-bearing f of the beater, and in the slot I adjustably secure a stud-pin, i, on which the gear-wheel k and sprocket-wheel l are journaled, as best seen in Fig. 11 95 of the drawings. It will be observed that the slot g is thus divergent from the axle A, and by shifting the stud-pin i in the slot g, so as to carry it from the axle A, the drive-chain m becomes tightened.

The actuating mechanisms of the traveling floor and beater are thrown in and out of gear by means of a shifting-lever, M, pivoted on the frame of the body O, and engaging at its rear end the clutch o. At the forward end of 100 the lever M is an arm, K, pivoted to a stud-pin secured to the body O, as shown in Fig. 9 of the drawings. The pivoted end of this arm is formed with a hub, K', provided with a spiral rib, G, similar to a worm or screw, and 105 to this is connected the end of the lever M, which is provided with a correspondingly grooved eye, embracing the hub K'. By swinging the arm K on its pivot the worm G thereof imparts a lateral motion to the lever 110 M, and the motion of the latter throws the clutch o in and out of connection with the clutch-face n'.

To the forward end of the body O is pivoted 115 a hand-lever, H, which is connected with the free end of the arm K by means of a rod, I, which passes freely through the said arm and is provided at its extremity with a nut or coupling-pin, and between the lever K and hand-lever H the rod I has secured to it a collar, l, and between this collar and the free end of the lever K is a spiral spring, 2, encompassing the rod I, and pressing with its opposite ends, respectively, against the latter and the aforesaid collar. By this means I obtain 120 a spring-coupling between the hand-lever and clutch-shifting lever, which spring-coupling

allows me to set the hand-lever in such a position before starting the machine as to impart to the clutch the necessary pressure to cause it to automatically shift the clutch *o* and lock 5 the sprocket-wheel *C* and eccentric *e* on the ratchet-wheel *T* when the machine is set in motion.

To retain the hand-lever in its aforesaid set position, I employ a suitable latch, *L*, pivoted 10 on the body *O*, and engaging the aforesaid lever, as represented in Fig. 1 of the drawings; and in order to cause the hand-lever *H* to automatically throw the clutch *o* out of engagement with the clutch-face *n'*, and thus stop the 15 motion of the manure-carrying floor when the forward end of the latter has reached the beater *B*, I connect to the under side of the forward portion of body *O* a longitudinally-movable bar, *N*, which slides with one end in a 20 guide attached to the body *O*, and is provided on said end with a suitable collar or head, between which and the guide is arranged a spring, 4, which serves to crowd the bar *N* rearward. The opposite end of said bar is connected to 25 one of the arms of a bell-crank lever, 5, which is pivoted to a bracket attached to the forward portion of the body *O*. The other arm of the said bell-crank lever is connected with the latch *L* by a rod, 6. The arrangement of said 30 parts is such as to cause the latch *L* to be normally in position for holding the hand-lever *H* when the spring-actuated rod *N* is at rest.

The hand-lever *H* is under a constant strain of a spring, 8, which forces the said lever forward, and when said lever is drawn back by 35 the operator to set the clutch *o* for transmitting motion to the manure-carrying floor and beater *B*, it requires the hold of the latch *L* to retain said lever in its position. To the bar 40 *N*, I connect an arm, 7, which is arranged adjustable in its position, so as to be encountered by the forward-moving rear end of the traveling floor when the front end thereof arrives at the beater *B*. The collision of the said floor 45 with the arm 7 causes the bar *N* to be crowded forward, and by means of the bell-crank lever 5 and rod 6 it throws the latch *L* out of engagement with the hand-lever *H*, and so soon as this is released it automatically swings forward 50 under the influence of the spring 8, and thereby shifts the clutch *o*, so as to stop the motion of the traveling floor and beater.

By means of a hand-crank, 9, connected to the end of the shaft *U*, the latter can be rotated so as to carry the endless floor back to 55 occupy the bottom of the body *O*, to receive another load of manure to be spread.

Having described my invention, what I claim as new, and desire to secure by Letters 60 Patent, is—

1. The combination of the axle, traction-wheels, clutch-connections between said parts, traveling floor and its carrying-wheel and shaft, a ratchet-wheel rigidly secured to said 65 shaft, two pawls engaging the ratchet-wheel, a rock-arm, rods connecting said rock-arm

with the pawls and adapted to actuate the same alternately, an eccentric on the aforesaid axle, and a rod connecting said eccentric with the rock-arm, all combined and co-operating 70 substantially in the manner specified and shown.

2. The traveling floor composed of endless chains, slats secured crosswise to said chains and provided with recesses in one of the edges 75 at their top, and plates projecting from the opposite edges of the tops of the slats and countersunk in the recesses of the adjacent slats, substantially as described and shown.

3. In combination with the clutch-shifting 80 arm and hand-lever for operating the same, a spring-coupling between said parts to preliminarily impart to the clutch the necessary pressure to automatically tie the wheel to the shaft when the wheel is set in motion, substan- 85 tially as set forth.

4. In combination with the axle or driving shaft and sprocket-wheel attached thereto, a standard provided with a slot diverging from the axes of the sprocket-wheel, a stud-pin ad- 90 justably secured in said slot, a sprocket-wheel pivoted on said stud-pin, and a driving-chain connecting said sprocket-wheels, substantially as set forth and shown.

5. In combination with the driving-shaft 95 and sprocket-wheel mounted thereon, the standard *F*, provided with the journal-bearing *f*, and the segmental slot *g*, described from the center of said journal-bearing, the beater *B* and pinion *h*, journaled in said bearing, the 100 stud-pin *i*, adjustably secured in the slot *g*, the gear *k* and sprocket-wheel *l*, pivoted on said stud-pin, and the chain *m*, connecting said sprocket-wheels, substantially as de- 105 scribed and shown.

6. The combination, with the axle and traction-wheels mounted loosely thereon, of ratchet-wheels rigid on the axle, pawls on the traction-wheels engaging said ratchet-wheels, a power-transmitting wheel loosely on the axle, 110 clutch-faces respectively on one of the ratchet-wheels and power-transmitting wheel, and a clutch sliding on one of said clutch-faces and permanently connected therewith, and adapted to engage and release the other clutch-face, 115 substantially as set forth.

7. The combination, with the axle *A* and traction-wheels *W W*, mounted loosely thereon, of the ratchet-wheels *P P*, rigid on the axle, the pawls *T T* on the traction-wheels, 120 the sprocket-wheel *C*, mounted loosely on the axle, the eccentric *e* and clutch-face *n*, both rigidly attached to said sprocket-wheel, the clutch-face *n'* on the ratchet-wheel, and the shifting clutch *o*, adapted to connect the two 125 clutch-faces *n n'*, substantially as described and shown.

8. In combination with the body or box, the traveling floor, the spring-restrained clutch, shifting lever, and the latch for holding said 130 lever, an arm arranged movably under the forward portion of the body and adapted to

be encountered by the rear end of the traveling floor during its forward movement, and a lever and rod for transmitting motion from said arm to the latch, substantially in the 5 manner described and shown.

In testimony whereof I have hereunto signed my name and affixed my seal, in the presence

of two attesting witnesses, at Syracuse, in the county of Onondaga, in the State of New York, this 10th day of July, 1886.
